ELECTROLYTIC AND SAPONIFYING PROCESS FOR PRODUCING NITRILE DERIVATIVES.

1,194,354.

Specification of Letters Patent. Patented Aug. 15, 1916.

Application filed February 23, 1915. Serial No. 9,955.

To all whom it may concern:

Be it known that I, JOHN E. BUCHER, a citizen of the United States, residing at Coventry, in the county of Kent and State 5 of Rhode Island, have invented certain new and useful Improvements in Electrolytic and Saponifying Processes for Producing Nitrile Derivatives, of which the following is a specification.

- 10 This invention relates to an improved process by means of which oxamid may be so cheaply and practicably produced as to permit of the use of this hitherto quite costly substance commercially for fertilizing purposes and the like. That oxamid could be produced from, for example, cyanogen by treating the latter with aldehyde was announced by von Liebig in 1860 (Ann. 113, p. 246); and in 1867, Schmitt and Glutz 15 (Ber., 1, p. 66) communicated the fact that when cyanogen gas is brought into contact with aqueous concentrated hydrochloric acid, the latter at first remains colorless, but that after twelve hours standing, crystals of oxamid separate from the cyanogen saturated acid while small quantities of ammonium oxalate are also formed. So far as I am aware nothing further appears to have been done looking to the practical development of a process for producing oxamid 20 either from cyanogen or a compound thereof and the object of the present invention is to provide a process whereby substantially pure oxamid can be produced on a large scale easily and cheaply and with a minimum number of operations or steps.

In the drawing which forms a part hereof I have shown, in part diagrammatically, an apparatus wherein my process may be effected.

The figure is a somewhat diagrammatic vertical median section of an electrolyzing chamber with a tower connected thereto.

Herein, the said chamber designated 1 45 contains a mass 2 of a cyanogen compound, such as sodium cyanid, which is to be decomposed with liberation of cyanogen at the positive pole 3. The latter may be of graphite and is preferably inclosed as at 4 50 to prevent contact of the liberated cyanogen with liberated sodium which passes through

the conduit 5, in liquid or vaporous form, from the electrolyzing chamber. The walls of the latter may be of cast iron and the mass to be treated therein is heated to, let us 55 say, 550° to 600° C., or sufficiently to liquefy the cyanid introduced by means of the screw conveyer 6, or the like; the heating being effected conveniently by low voltage current supplied by a lead 7 to the positive pole 60 electrode 3, said current after traversing the charge to the negative pole electrode, i. e. the container or receptacle 1, passing thence via a lead 8. The inclosure 4 may also be of magnesia brick, or other suitable substance supported by the container 1; the latter also resting upon insulation 9, and the electrode 3 being spaced up from the bottom of the container by means of an insulating block 10. The liberated cyanogen may be 65 drawn off through a conduit or pipe 11, by means of a centrifugal pump 12, or the like, a valve 13 being provided to regulate the gaseous flow and to prevent the entrance of air to the chamber 1 when the pump is not 70 in operation. The sodium may be collected in a condensing chamber 14, for use in connection with the process described in my Patent No. 1,082,845, dated December 30, 1913, for reforming cyanid for continuing 75 the present process.

The cyanogen leaving the pump passes preferably to the lower end of a tower or scrubber 15, similar to those used in the ammonia-soda process; the tower having therein perforated baffles 16 through which flows preferably strongly concentrated hydrochloric acid, which may, if desired, be pre-heated or it may be warmed by hot cyanogen gas supplied thereto, in order to produce 80 the best initial results; although, as the reaction is strongly exothermic, the tower or the like will in some cases have to be cooled during the course of the operation.

The receptacle 1 and connections therefrom to the tower should be air tight and the electrolytic liberation of this poisonous gas and immediate introduction thereof into a tower where all of said gas is converted into the product or products sought affords 95 a particularly advantageous way of conducting the process herein described. The acid

enters through the pipe 17 at the upper end of the tower and acts catalytically upon the cyanogen to form oxamid according to the equation:

If the acid be not sufficiently cooled oxalic acid will be formed, as follows:

the acid hence being used up with a resultant formation of ammonium chlorid, and the oxalic acid separating out as a thick crystal paste, on cooling. The solubility curves of oxalic acid and ammonium chlorid differ very greatly so that there is no difficulty in separating these products.

20 One mode of conducting the present process hence affords a very cheap production of oxamid while another yields somewhat less cheaply but very conveniently, oxalic acid. Even if sufficiently cooled hydrochloric acid 25 be not used and oxalic acid be formed, the catalyster may still be recovered by treating the ammonium chlorid formed with sulfuric acid to get as a by-product the commercially valuable ammonium sulfate. Oxamid is 30 however very valuable as a fertilizer as it has nearly 32% of nitrogen and does not readily lixiviate out of the soil; but it does not appear heretofore to have been so used, probably on account of its cost which until 35 now has been practically prohibitive for this purpose. Furthermore, as another aspect of the present invention, commercially concentrated hydrochloric acid of, say, sp. gr. 1.14, may be readily converted to stronger acid by 40 treating it with cyanogen; since the oxamid forming reaction vigorously abstracts the water from the acid. I desire to point out, however, that in order to secure results which are of highest commercial value, the 45 acid must become saturated with cyanogen and this saturation must be maintained. It is also highly desirable to strongly agitate the solution and this, of course, is readily and inexpensively accomplished in the scrubber, while operating as above described. The reaction may also be furthered by 50 increasing the concentration of the cyanogen in solution in the catalyster by introducing it thereinto under moderate pressure and while 55 the temperature of both the catalyster and the cyanogen gas are correspondingly somewhat elevated. Indeed, without the use of pressure, at 100° C., hydrochloric acid of sp. gr. 1.18 would necessarily give off much HCl 60 gas, thus becoming more dilute and at the same time crowding out the cyanogen gas by reducing its partial vapor pressure above the liquid. Also, the physical solubility of the cyanogen in the liquid should almost dis- 65 appear at 100° C. and under atmospheric

pressure. If, therefore, the latter pressure be used the above factors must be more fully considered and the oxamid formation must be effected at a correspondingly lower temperature, preferably about 40 or 50° C.; since 70 there is a distinct maximum yield of both oxamid and oxalic acid (the product or mixture of products depending upon the amount of water present in the acid, and the temperature) when operating under a determined 75 pressure; this yield being obtainable by the use of the proper temperature corresponding to such pressure. As the cited reactions are exothermic, a rise in temperature during the course of the oxamid or oxalic acid formation is to be expected and should preferably be considered in view of the above. In other words if atmospheric pressure is used, the tower or like apparatus should preferably be cooled. The oxamid precipitate obtained is 80 usually granular and shows little if any tendency to incrust the apparatus, while the acid remaining therein evaporates off readily with but little decomposition of the oxamid. Even this small loss may be practically entirely avoided by distilling off the hydrochloric acid *in vacuo*. 85

I have laid emphasis in the foregoing upon the desirability of both maintaining the acid saturated and agitating the same, and the following experiment may be cited in proof thereof: A 200 cc. glass bottle containing concentrated hydrochloric acid was connected with a cyanogen gas container through the intermediacy of a burette. 90 Upon shaking the bottle there was a sudden rush of cyanogen thereinto until the liquid became saturated by physical absorption in from 10 to 20 seconds. As long thereafter as the shaking was continued there was a steady chemical absorption of cyanogen which was measured in the burette and this gave a very quick and accurate method of determining the rate of oxamid formation, since the saturation of the liquid catalyster was maintained. When the shaking was stopped, the physical absorption also practically ceased, but the chemical action continued so that the liquid rapidly became unsaturated with respect to the cyanogen gas. 95 The bottle was then suddenly shaken after a minute or so, when again there was a jump of water in the burette, showing that almost instantaneous absorption occurred, to make up for the unsaturation developed while the 100 bottle was at rest. The steady chemical absorption was then allowed to proceed as before. From measurements of gas absorption, obtained in the manner just indicated, I consider that it is probable that the saturated liquid contains four or more times its volume of cyanogen and that even in such a simple apparatus, at 37° C., 15 cc. of HCl can convert its own volume, 15 cc., of cyanogen gas into oxamid every minute, which 105 110 115 120 125

is at the rate of about 3.3 grams of oxamid per hour.

By means of the above simple apparatus I have also determined that at 20° C., 15 cc. of commercial concentrated hydrochloric acid of about 1.14 sp. gr. (28° Tw.) will only absorb about 1 cc. of cyanogen in 30 seconds; while acid of 1.18 sp. gr. under identically the same conditions will absorb about three times as much gas, which shows the strong retarding influence of dilution.

Hydrobromic acid, while more expensive than hydrochloric acid, is nevertheless adapted for use in the process as a catalyst, and indeed gives even a still more rapid rate of oxamid yield. Hydriodic acid, however, while giving a still more rapid formation of oxamid is expensive, and moreover this acid is destroyed during the course of the reaction; the iodin separating therefrom and contaminating the product sought. The rise in temperature of the reactive mass is also objectionably pronounced. Even when using hydrochloric acid, for example, of sp. gr. 1.14, or thereabout, if the temperature in the tower be permitted to rise unduly for the given operating pressure, whether this be atmospheric, above that of the atmosphere, or even below, as may be found advantageous in certain cases, there is a tendency to form oxalic acid, which contaminates the oxamid produced and in addition uses up some of the catalyst.

When conducting the operation at the room temperature, or thereabout, I prefer to introduce about 36 pounds of water with each 52 pounds of cyanogen gas entering the tower, because, as previously stated, the process steadily concentrates the hydrochloric acid by removing the water therefrom to form oxamid, and if water be not so added, either continuously or intermittently, there would presently be given off from the tower a current of anhydrous hydrochloric acid gas while the apparatus would finally contain only solid oxamid with no liquid present, and action would cease. The water of course may be added in the form of dilute acid with the two-fold result of supplying the requisite water to the reaction and of concentrating this dilute acid. Since the oxamid is so very slightly soluble in water or in the acid, the resultant concentrated acid is almost chemically pure. Further, constant boiling HCl, sp. gr. 1.13 may thus be concentrated to, say, sp. gr. 1.20, at sufficiently low temperatures or under pressure, and this acid may then be heated to drive off large volumes of HCl gas until the acid again approaches sp. gr. 1.13; after which the acid may be cooled, or introduced into the tower under pressure, and the cycle repeated. This, hence, affords a method of obtaining hydrochloric acid gas from an acid of but moderate concentration

while the latter acts as a catalyst to simultaneously form a product (oxamid) which is substantially insoluble in said catalyst.

I may here mention that with any concentrated hydrochloric acid, if the temperature is raised much above that of the room, there is a tendency to form oxalic acid as well as oxamid, and since oxalic acid is slightly decomposed at temperatures approximating 100° C., in the presence of relatively strong hydrochloric acid, it is preferable to operate at lower temperatures to avoid decomposition of the oxalic acid formed and to recover such acid by subsequent heating *in vacuo*.

I have ascertained that diluting hydrochloric acid sp. gr. 1.18, with an equal bulk of water, slows down the oxamid forming reaction some 120 fold, indicating that the strength of the acid properties is not of primary importance in the oxamid forming reaction, since such a solution would still have over 50% of its original acidity and this supports my theory that the hydrochloric acid first added to the water is used up in combining with the water molecules until a concentrated solution is formed; and that after the affinity of the water has been satisfied, further increase in concentration of the hydrochloric acid gives a chance for the excess acid molecules to form unstable addition products of hydrochloric acid with the cyanogen itself, which products then decompose to give the exceedingly efficient oxamid formation.

The following remarks show the enormous importance of the opposing factors, above referred to, their relative magnitude, and how best to overcome the unfavorable ones.

(a) Temperature increase from 0° to 90° C. lowers the solubility of cyanogen in water from about 8 volumes to about 1.2 volumes and hence retards oxamid formation about 6½ fold from this cause.

(b) Temperature increases the tension of HCl from the solution by fully $\frac{1}{2}$ of an atmosphere at about 40° C. for 1.18 sp. gr. acid; thus theoretically reducing the partial pressure by about 33%; while with stronger acid or a somewhat higher temperature and with certain forms of apparatus, this opposing action becomes substantially infinite and no oxamid forms.

(c) Increase of temperature from 20° to 40° C. apparently increases the rate of oxamid formation about 4 fold after allowing for the retarding action under a and b.

(d) Pressure greatly increases oxamid formation by forcing very much more cyanogen into the solution.

(e) Incidentally, it allows the use of much stronger HCl, above that of the constant boiling mixture of HCl and water, by forcing more gaseous HCl into the liquid and it also overcomes the serious opposing effect

- under *b*; *i. e.*, it allows a volatile catalyzer, in excess of that forming a constant boiling mixture, to be forced into and held in the reaction mixture. Also, in general, it holds 5 the large excess of volatile catalyzer in solution which is so essential when rapid formation of oxamid is desired at moderate temperatures and when oxalic acid formation is to be substantially avoided.
- 10 (f) By pressure, cyanogen may be pressed or liquefied into the reaction mixture in such quantity that it combines with much or all the water so as to release much or all the HCl gas from the solution. This gas can 15 then be allowed to escape by releasing the pressure and the cycle repeated.
- (g) In tubes at atmospheric pressure, it takes about 28 minutes at 20° C. to form a precipitate of oxamid while under the pressure of liquid cyanogen (4 atmospheres) at 20 the same temperature, the time is reduced to about 7 minutes, thus showing a 4-fold increase (as it should be) by pressure alone. When the tube is shaken in water at 50° C., 25 the time is reduced to 40 seconds or 10-fold; chiefly by temperature effect alone. This gives about a 40-fold increase due to temperature and pressure combined from 20° to 50° C. and of over 200-fold, if we 30 strengthen the acid from 1.14 to 1.22 sp. gr.
- (h) If the acid of 1.18 sp. gr. is strengthened by cooling to perhaps 0° C. or lower, and saturating further with HCl gas, "fuming" hydrochloric acid may be obtained 35 of about 1.22 sp. gr., or 45% HCl, which gives double the rate of action over that given by the 1.18 sp. gr. or 36% HCl. Also, by diluting the acid of sp. gr. 1.18 with an equal bulk of water, we reduce the 40 rate about 120 fold while by saturating it at about 0° C. the rate is doubled. This gives an increase of 240-fold in passing from a 16% acid to one of about 45% of HCl.
- Sulfuric acid, sp. gr. 1.55 and nitric acid 45 of sp. gr. 1.33 act so slowly, if at all, that I cannot measure the action by the methods above indicated, which shows again that the mere strength of acid properties is not primarily concerned in the reaction; and the 50 action, moreover, seems to be exerted particularly by the halogen acids. Finally I may add, that in one case, I added a small quantity of cuprous chlorid to the hydrochloric acid and apparently got increased 55 activity. Cuprous chlorid forms an addition product with cyanogen and may hence have acted as an auxiliary catalyst.

In certain of the appended claims wherein 60 by reason of the objection to the use of alternative expressions in the claims, hydrochloric acid is mentioned, it is to be understood that such expression is not to be regarded as limiting such claims specifically to said acid; since hydrobromic acid is to all

intents and purposes an equivalent for hydrochloric acid in the process. The term hydrochloric acid is hence to be regarded as of sufficient breadth to cover this equivalent and is employed in this fashion to avoid cumbrous and circuitous expression and also 70 alternativeness in said claims.

Having thus described my invention what I claim is:—

1. The process of producing oxamid which comprises conducting gaseous cyanogen into a bath of aqueous concentrated halogen acid the temperature of which is insufficient to permit the formation of appreciable quantities of oxalic acid, to form the product sought. 75

2. The process of producing oxamid which comprises conducting gaseous cyanogen into a bath of aqueous concentrated halogen acid the temperature of which is insufficient to permit the formation of appreciable quantities of oxalic acid, to form the product sought, said bath being maintained substantially saturated with cyanogen during the reaction. 85

3. The process of producing oxamid 90 which comprises conducting gaseous cyanogen into a heated bath of aqueous concentrated halogen acid under temperature conditions which do not permit the formation of appreciable quantities of oxalic acid to 95 form the product sought.

4. The process of producing oxamid which comprises conducting gaseous cyanogen into a bath of aqueous concentrated halogen acid under temperature conditions 100 which favor the production of oxamid and agitating said bath while the gas is in contact therewith, to maintain the cyanogen saturation thereof.

5. The process of producing oxamid 105 which comprises conducting gaseous cyanogen under pressure into an aqueous bath of catalytic material capable of combining the water present in said bath with said cyanogen to form oxamid. 110

6. The process of producing oxamid which comprises conducting gaseous cyanogen under pressure into an aqueous bath of halogenous catalytic material capable of combining the water present in said bath 115 with said cyanogen to form a product substantially free from halogen of said catalytic material.

7. The process of producing oxamid which comprises liberating gaseous cyanogen from a cyanogen compound, and treating the so liberated gas with a concentrated halogen acid the halogen of which is normally incapable of being liberated in molecular condition in the presence of cyanogen 125 and water under the temperature conditions of the operation, to cause said acid to catalytically combine the water present therein.

with the cyanogen, and replacing the so combined water by an amount substantially just sufficient to continue the operation.

8. The process of producing oxamid which comprises electrolyzing a cyanogen compound to liberate gaseous cyanogen therefrom, collecting the latter and commingling therewith a concentrated halogen acid the halogen of which is normally incapable of being liberated in molecular condition in the presence of cyanogen and water under the temperature conditions of the operation, to saturate said acid with said cyanogen, and maintaining said acid substantially saturated while combining the water thereof with said cyanogen, to form the product sought.

9. The process which comprises effecting a vigorous exothermic reaction upon the water present in a mass of concentrated halogen acid, with cyanogen, while agitating said acid to maintain the same saturated with said cyanogen and maintaining the temperature of said mass within determined limits dependent upon the pressure under which the reaction is effected, the temperature being such as will avoid an outrush of gaseous acid from said mass while favoring a high content of cyanogen therein.

10. The process which comprises effecting a vigorous exothermic reaction upon the water present in a mass of concentrated halogen acid, with cyanogen, while agitating said acid to maintain the same saturated with said cyanogen and maintaining the temperature of said mass within determined limits dependent upon the pressure under which the reaction is effected, the temperature being such as will avoid an outrush of gaseous acid from said mass while favoring a high content of cyanogen therein, the upper temperature limit being established by cooling said mass during the progress of said oxothermic reaction.

11. The process which comprises effecting a vigorous exothermic reaction upon the water present in a mass of concentrated halogen acid, with cyanogen, while agitating said acid to maintain the same saturated with said cyanogen and maintaining the temperature of said mass within determined limits dependent upon the pressure under which the reaction is effected, the temperature being such as will avoid an outrush of gaseous acid from said mass while favoring a high content of cyanogen therein.

12. The process which comprises effecting a vigorous exothermic reaction upon the water present in a mass of concentrated halogen acid, with hot cyanogen gas, while agitating said acid to maintain the same saturated with said cyanogen and maintaining the temperature of said mass within determined limits dependent upon the pressure

under which the reaction is effected, the temperature being such as will avoid an outrush of gaseous acid from said mass while favoring a high content of cyanogen therein.

13. The process of obtaining oxamid which comprises effecting a vigorous exothermic reaction upon the water present in a mass of concentrated halogen acid while maintaining the temperature of said mass substantially constant, and keeping the water content thereof sufficiently low to permit said acid to act substantially solely as a catalyst and, while thereby avoiding loss of said catalyst, to produce a product free from halogenous impurities.

14. The process which comprises effecting a vigorous exothermic reaction under pressure upon the water present in a mass of concentrated halogen acid, with cyanogen, while agitating said acid to maintain the same saturated with said cyanogen and maintaining the temperature of said mass within determined limits dependent upon the pressure under which the reaction is effected, the temperature being such as will avoid an outrush of gaseous acid from said mass while favoring a high content of cyanogen therein.

15. The process which comprises effecting a vigorous reaction upon the water present in a mass of aqueous concentrated halogen acid, with cyanogen to combine said water with at least one element of said cyanogen, and supplying water to said mass, to compensate for that taken from said acid, by introducing acid of less concentration, whereby to continue the reaction.

16. The process which comprises effecting a vigorous reaction upon the water present in a mass of aqueous concentrated halogen acid, with cyanogen, to combine said water with at least one element of said cyanogen, and supplying water to said mass to compensate for that taken from the acid, to prevent the latter from being driven off in a gaseous form.

17. The process of combining cyanogen with water which comprises reacting upon an aqueous solution of a catalyst which is normally gaseous when free and which solution is more strongly concentrated than is the constant boiling mixture of water and said catalyst, to catalytically combine some at least of the water, in which is dissolved said catalyst, with said cyanogen.

18. The process of combining cyanogen with water which comprises holding a large excess of a volatile catalyst in water by pressure and reacting catalytically upon said water with cyanogen to form a product which is substantially insoluble in said water and catalyst.

19. The process of obtaining a substantially pure catalytic substance which comprises subjecting an aqueous solution of a

volatile catalyst to a determined pressure while combining water of said solution with cyanogen through the instrumentality of said catalyst, to concentrate said solution, 5 effecting a lowering of said pressure to permit of the volatilization of a part of said catalyst, and continuing to react upon the now more dilute solution with cyanogen at a pressure above that at which said volatilization of catalyst occurred.

20. The process of producing substantially chemically pure and very highly concentrated halogen acid which comprises reacting with cyanogen upon an aqueous concentrated halogen acid, to combine the water present in said acid with said cyanogen to form oxamid.

21. The process of producing substantially chemically pure and very highly concentrated hydrochloric acid which comprises reacting upon aqueous concentrated hydrochloric acid with cyanogen at a temperature and under pressure conditions corresponding thereto which effects the combination of the aqueous content of said acid with said cyanogen to form substantially only oxamid.

22. The process of producing gaseous hydrochloric acid which comprises reacting

upon aqueous concentrated hydrochloric acid with cyanogen to form cyamid and more 30 highly concentrate said acid, removing a portion of the acid in gaseous form, and re-concentrating the remaining less concentrated acid by continuing the treatment thereof with cyanogen preparatory to again 35 removing the gaseous acid therefrom.

23. The process of producing absolute hydrochloric acid which comprises reacting upon aqueous concentrated hydrochloric acid with cyanogen to remove water therefrom, 40 and then removing the acid in gaseous form from the residues of said reaction.

24. The process of producing hydrochloric acid which comprises reacting upon aqueous concentrated hydrochloric acid with 45 cyanogen under pressure, to remove water from said acid, and then lowering the pressure upon the liquid under treatment to allow a portion of the acid to escape therefrom in gaseous form.

In testimony whereof I have affixed my signature, in the presence of two witnesses.

JOHN E. BUCHER.
